UNITED STATES PATENT OFFICE

ELBERT RICHARD POTTER, OF VILLA PARK, ILLINOIS, ASSIGNOR TO HARRY A. HIRST,
OF CHICAGO, ILLINOIS

SPEED-UP HAIR CLIPPER

Application filed August 15, 1928. Serial No. 299,823.

My invention relates to hair clippers and more particularly to a novel construction of speed-up hair clipper of simple form capable of economical manufacture and so geared or constructed that the rapidity of reciprocation of the cutter blade may be increased and which, while hand-operated, has a relatively high speed ratio, preferably from twelve to sixteen to one—that is from twelve to sixteen movements of the cutter bar to one movement of the operating handle or lever, whereby a barber may secure greater speed in clipping hair with less effort than with hand clippers at present in use and without hair pulling and still avoid the objection to electric clippers which are difficult to control and can only be used in a first or rough cutting operation.

Another object of the invention is to provide a hair clipper having a handle in the form of a casing adapted to house the working parts or gearing for driving the reciprocating toothed cutter blade and an oscillatory handle or lever pivoted to the stationary part or casing and operatively connected to the driving means or gearing; the oscillatory handle being held outward by a spring capable of adjustment; to provide means for limiting the outward movement of the oscillatory handle as well as the inward movement thereof; to provide means for securing proper positioning and tensioning of the pressure plate on the cutter blade without interfering with the movement of a rocking lever constituting a part of the operating mechanism associated with a crank wheel or disk driven by gearing operatively connected to the movable handle member and to generally improve and enhance the value and efficiency of devices of this class.

With the above and other objects in view, the invention consists in certain novel structure and arrangement of parts to be herein-after more particularly specified and pointed out in the claims.

In the accompanying drawings:

Figure 1 is a plan view of a hair clipper constructed in accordance with the invention.

Fig. 2 is a side elevation of the device.

Fig. 3 is a bottom view.

Fig. 4 is a transverse horizontal sectional view, through the casing, showing the gearing and other parts in elevation.

Fig. 5 is a central vertical longitudinal sectional view taken on the section line 5—5 of Figure 4.

Figs. 6 and 7 are cross sectional views taken on the section lines 6—6 and 7—7 of Figure 4.

Fig. 8 is a vertical sectional view taken on the section line 8—8 of Figure 4.

Fig. 9 is a sectional view taken on the section line 9—9 of Figure 5.

Fig. 10 is a sectional view taken on the section line 10—10 of Figure 5, and

Fig. 11 is a sectional view taken on the section line 11—11 of Figure 4.

Referring to the drawings in detail, my hair clipper is shown as comprising a casing 1 forming a hollow stationary handle including a bottom plate 2 over which the cover 3 of the casing is secured as by means of screws 4 engaging internal lugs 5 on the inside of the downturned flange surrounding the cover, thus detachably connecting these parts and rendering it possible to easily assemble or disassemble the casing for obtaining access to the interior parts to be subsequently described. The front end of the bottom plate 2 is disposed horizontally at an obtuse angle as indicated at 6 and has a plate 7 mounted thereon. A stationary toothed or bottom cutter blade 8 is secured to the plates 6 and 7 as indicated at 9, whereby it may be removed for sharpening.

Rectangular guide pins 10 are screwed or otherwise mounted on the stationary blade 8 and an upper or movable toothed cutter blade 11 is mounted to reciprocate on the blade 8 and has a pair of slots 12 engaging the guide pins 10. The movable cutter blade 11 is recessed at the back as indicated at 13 for a purpose to presently appear.

An upright post 14 in the form of a screw having a threaded portion 15' engaged in threaded apertures in the plates 6 and 7 and its head 15 seated in the top recess 16 of the stationary blade 8 is centrally mounted in rear of the recess 13. A cylindrical housing 17 is mounted on the plate 7 at one side and in rear of the post 14 and has a plate portion 18

engaging the post 14 and overlying the plate 7, to which it is suitably anchored.

A movable or oscillatory lever or handle member 19 has a hub or sleeve portion 20 pivoted on the post 14 and engages the outer end of an expansible coil spring 21 disposed within the cylindrical housing 17 and against the end wall of a hollow plug 22 threaded in the housing 17 so as to adjust the tension of the spring 21. The handle member 19 is limited in its outward movement by a stop or pin 23 constituting one of the connecting means for the plates 6, 7 and 18, and in its inward movement by a stop lug 24' on the top face of the handle member 19 adjacent the sleeve 20 engaging the adjacent end of the cylindrical housing. The spring 21 normally holds the handle member 19 outward or away from the stationary handle member produced by the casing 1, which latter extends rearwardly centrally of the cutter blades.

Means are provided for rapidly reciprocating the movable cutter blade 11 by movement of the lever or handle member 19 so as to reciprocate the cutter blade by oscillation of the handle member.

For this purpose, a spur gear 24 is mounted to freely turn on the screw post 25 carried by the bottom plate and has an eccentric pin 26 on which is pivoted a connecting rod or pitman 27 which extends through an opening 28' in the side of the cover 3 of the casing 1. Its outer end is pivoted between spaced ears 28 of a bracket 29, attached to the inner face of the handle member 19, on a pin 30 in the form of a screw threaded into one of the ears as indicated at 31. The gear 24 meshes with a pinion 32 on a screw post 33 also carried by the bottom plate 2. A spur gear 34 is fixed to the pinion 32 and engages a pinion 35 rotatable on a stud shaft 36 extending upwardly from the plate 2. The pinion 35 on the shaft or arbor 36 bears on a bearing 37 to secure the proper elevation of the pinion 35. A crank disk 38 which also acts as a flywheel, is rotatable on the shaft 36 and is detachably held in position by a washer and spring ring 39. The disk 38 has a crank pin 40 rotatably mounted therein eccentrically and retained in position by a similar washer or spring 41. The upper end of the pin is enlarged to form a shoulder resting on the top face of the crank disk and has a diametrical opening 42 slidably receiving the cylinder end 43 of a rock lever 44.

This rock lever is bent to conform to the interior parts so that it will be best to accommodate it within the casing and to establish clearance. Its lower end is bent horizontally and apertured to pivot on the post as indicated at 45, preferably with an interposed bushing 46 and is then bent downwardly as indicated at 47 to engage in the recess 13 of the movable cutter blade. A pressure plate 48 is mounted on the post 14 to engage with

slight friction the top face of the movable cutter blade 11 and has a pair of lugs 49 projecting downwardly in its rear edge to engage the front end of the cover 13 or the top of the housing 17 to prevent the pressure plate bearing on the lever 44 and insure that it will be tilted slightly forwardly against the reciprocating cutter blade. The pressure plate has a lug 50 with a rectangular opening engaging one of the guide pins 10 to properly position the pressure plate and when so mounted, it is held with slight pressure by a concavo-convex spring washer 51 disposed on the post against the top of the pressure plate and the front end of the cover 3 and a thumb nut 52 threaded thereover to regulate this pressure.

In the operation of the device, the spring 21 normally holds the lever or handle member 19 outward on the post or pivot 14, the tension of the spring being capable of adjustment by reason of the plug or nut 22 so as to secure the proper tension. When the barber is using the device he grasps the handles and exerts pressure on the member 19, forcing it inwardly against the tension of the spring 21. In doing this, the gear 24 is caused to oscillate by reason of its connection with the member 19 by the connecting rod 27. As the gear 24 rotates in mesh with the pinion 32, rotation is thus imparted to the gear 34 in an opposite direction at increased speed. This rotation is in turn imparted to the crank disk 38 from the gear 34 by the meshing of the latter with the pinion 35 fixed to the crank disk at an increased speed ratio, causing the crank disk to be rotated at high speed. As the crank disk rotates, the rock lever 44 will be rapidly oscillated on its pivot 14 above the sleeve 20 of the member 19, and due to the sliding engagement of the lever 44 at its circular portion 43 with a corresponding diametrical aperture of the pin 40, the latter will slide back and forth on the portion 43 as the crank disk rotates. This operation is effected without any degree of friction or noise. As the lever 44 is rocked, the movable cutter blade 11 will be rapidly reciprocated across the stationary cutter blade to secure high efficiency in cutting the hair.

By reason of the washer 51 and nut 52 the pressure plate will be pressed forwardly to secure proper coaction between the respective cutter blades. This is facilitated by having the rear edge of the washer resting on the front end of the casing or cover plate 3. This device may be easily controlled, the same as any ordinary hand clipper. It also may be operated with as much ease but with greater speed and efficiency. As before stated, the movement of the lever 19 when forced outward by the spring 21 is limited by the pin 23 and its inward movement is limited by the pin 24' engaging the end of the housing 17. The speed ratio between the movement of

- the lever 19 and the movable cutter blade is preferably from twelve to sixteen to one—that is, for each inward or outward movement of the handle member or lever 19, the 5 movable cutter blade will be moved in opposite directions from twelve to sixteen times according to the number of the teeth in the gearing and the ratio established therebetween.
- 10 While I have shown and described my invention in a preferred form, I am aware that various modifications and changes may be made therein without departing from the principles of the invention, the scope of which 15 may be determined by reference to the appended claims.
- I claim as my invention:
1. In a speed-up hair clipper, a casing forming a handle, a stationary cutter blade carried by the casing, a movable cutter blade 20 slidable on the stationary cutter blade, a lever pivoted on the casing and normally spring-pressed outwardly, a gear train mounted in the casing, a connecting rod between the lever and gear train operating through an opening in one side of the casing handle adapted to oscillate and impart rotation to the gear train in opposite directions, said gear train including a crank disk 25 in the rear part of the handle, and a rock lever pivoted near the forward end of the casing, operatively connected to the movable cutter blade extending over the gear train and slidably connected to the crank disk at 30 its free rear end.
  2. In a speed-up hair clipper, a casing extended back to form a hollow handle, a stationary cutter blade carried by the casing, a movable cutter blade, a lever pivoted forwardly of the casing and normally spring-pressed outwardly, a rock lever pivoted on the pivot of the first-named lever and having a depending portion connected to the movable cutter blade, a gear train in the 45 handle of the casing including a crank disk having a rotatable pin with a diametrical aperture receiving the outer end of the rock lever for sliding movement therein as the crank disk is oscillated to impart reciprocation to the movable cutter blade, and a connecting rod operating through one side of the casing pivoted to the first-named lever and to one of the gears of the gear train to oscillate the latter upon oscillation of the 50 first-named lever.
  3. In a hair clipper, a casing including a bottom plate having its forward end directed horizontally and a rearwardly extending hollow handle, a stationary cutter blade attached thereto, a movable cutter blade mounted to reciprocate on the stationary cutter blade, an upright post on the plate, a handle pivoted to the post, a housing on the plate having a spring therein engaging the handle tending to force it outward
  4. In a hair clipper, a casing including a bottom plate having its forward end directed horizontally and a hollow stationary handle, a stationary cutter blade attached thereto, a movable cutter blade mounted to reciprocate on the stationary cutter blade, an upright post on the plate, a handle pivoted to the post, a housing on the plate having a spring therein engaging the handle tending to force it outward on its pivot, 95 means to limit the outward movement of the handle, means to limit the inward movement of the handle, a cover on the plate forming a part of the casing and hollow handle and having an opening in one side, a pressure plate on the pivot to hold the movable cutter blade against the stationary cutter blade, a gear train rotatably mounted on the plate beneath the cover, a connecting rod pivoted to the handle and the lowermost gear of the gear train through the opening, said gear train including a crank disk having an eccentric opening, a pin loosely held in said opening to permit the crank disk to turn relative thereto, a rock lever in the hollow handle and also pivoted on the post and having a circular end slidably engaging a diametrical opening through the pin on the crank disk, the front end of the rock lever being turned down and engaging in a recess in the movable cutter blade to reciprocate the latter at high speed upon oscillation of the handle, 100 through said gear train.
  5. In a hair clipper, a casing including a bottom plate having its forward end directed horizontally and a hollow stationary handle, a stationary cutter blade attached thereto, a movable cutter blade mounted to reciprocate on the stationary cutter blade, an upright post on the plate, a handle pivoted to the post, a housing on the plate having a spring therein engaging the handle tending to force it outward on its pivot, 105 means to limit the outward movement of the handle, means to limit the inward movement of the handle, a cover on the plate forming a part of the casing and hollow handle and having an opening in one side, a pressure plate on the pivot to hold the movable cutter blade against the stationary cutter blade, a gear train rotatably mounted on the plate beneath the cover, a connecting rod pivoted to the handle and the lowermost gear of the gear train through the opening, said gear train including a crank disk having an eccentric opening, a pin loosely held in said opening to permit the crank disk to turn relative thereto, a rock lever also pivoted on the post and having a circular end slidably engaging a diametrical opening through the pin on the crank disk, the front end of the rock lever being turned down and engaging in a recess in the movable cutter blade to reciprocate the latter at high speed upon oscillation of the handle through said gear train, said rock lever extending over the gear train for engagement with the crank disk pin within the casing.
  6. In a hair clipper, a casing, a stationary cutter blade carried thereby, a movable cutter blade mounted to reciprocate on the stationary cutter blade, an upright post on the casing, a handle pivoted to the post, means 120

to hold the handle in one direction, said casing having a flat bottom plate and a cover and forming a hollow handle, a lever pivoted on the post and engaging the movable cutter blade, a gear train in the rear part of the casing operatively connected with the lever, and an operative connection between the pivoted handle intermediately and the forward gear of the gear train through one side of the hollow handle.
